Charles W. Kettron, ^{INVENTOR.}
By. LaPorte v. Beam.
Atty's.

UNITED STATES PATENT OFFICE.

CHARLES W. KETTRON, OF MACOMB, ILLINOIS, ASSIGNOR TO ILLINOIS ELECTRIC POR-
CELAIN COMPANY, OF MACOMB, ILLINOIS, A CORPORATION OF ILLINOIS.

SPLIT INSULATOR.

Application filed February 4, 1916. Serial No. 76,111

To all whom it may concern:

Be it known that I, CHARLES W. KETTRON, a citizen of the United States, a resident of Macomb, in the county of McDonough and State of Illinois, have invented new and useful Improvements in Split Insulators, of which the following is a specification.

My invention relates to improvements in insulators and principally to these devices which are of the split type; that is, which are made and sold in two parts for convenience in attaching the wire thereto.

The principal object of this invention is the provision of a split insulator in which the parts are mounted on the securing means and prevented from complete separation, provision being made, however, for sufficient movement to enable the wire to be applied thereto.

A further object of this invention is the provision of a split insulator having the securing means passing therethrough and having a stop or abutment member thereon limiting the movement of the sections of the insulator relative to each other on the securing means, thereby permitting the application of the wire therebetween, but preventing the separation of the sections from each other and from the securing means.

Another object of this invention is the provision of a split insulator having securing means therethrough, the parts being movable relative to each other sufficiently to permit the application of a wire therebetween and complementary means on the parts to cause them to remain in proper alignment with each other.

Another object is the provision of a split insulator having the two parts mounted on the securing means and prevented from separation therefrom, but permitted to have movement relative to each other, so as to permit the application of the wire therebetween, one of the parts having a socket or recess and the other part having a projection or extension fitting in said socket or recess so as to hold the parts in their proper position relative to each other in application.

To the accomplishment of the foregoing and such other objects as may hereinafter appear, my invention consists in the combination, construction and arrangement of parts hereinafter described and then sought to be defined in the appended claims, refer-

ence being had to the accompanying drawings forming a part hereof, and which shows merely for the purpose of illustrative disclosure, a preferred embodiment of my invention, it being understood that various changes may be made in practice within the scope of the claims without digressing from my inventive idea.

In the drawings,

Figure 1 represents a side elevation of a device constructed according to my invention, the parts of the insulator being shown separated sufficiently to permit the application of a wire therebetween:

Figure 2 is a vertical longitudinal cross section showing the wire in position, and also indicating in dotted lines, the extent of the movement permitted between the two sections, whereby the wire may be moved into position in the wire receiving groove;

Figure 3 is a bottom plan view of the top or cap section or part of the insulator;

Figure 4 is a top plan view of the bottom part or section of the insulator.

Figure 5 is a perspective view of the underside of the top or cap section part of the insulator.

Split or two-part insulators are now in general and extensive use and are preferred because the wires may be clamped and held therewithout the necessity of using tie wires. As at present made, they are subject to the objection of being inconvenient in application for the reason that in installing them, the base must be placed against the surface, the wire in the groove in the base and then the cap must be selected and placed in proper position over the wire in the base and while these parts are being held in position, the installer must select the nail, screw or other securing means, place it in the hole through the sections of the insulator and drive the same with his hammer, screw driver or other tool. It is obviously seen that this consumes considerable time and makes the application of the split insulators a rather complicated procedure, particularly in view of the fact, that the larger part of the installing is done in places inconvenient for access, and in which the installer must assume a very cramped and tiresome position.

By the use of my invention, I obviate these objections to a large extent and provide a device having all the advantages of

the split insulator, and at the same time one which may be applied readily and with maximum efficiency.

Referring now to the drawing, the numeral 5 1 designates the top or cap section of the insulator and 2 the bottom or base section of the insulator, these parts having the aligned apertures 3 and 4 there-through, to receive the securing means which 10 I have shown in the form of a nail 5, it being expressly understood, however, that other securing devices may be just as readily used. These sections 1 and 2 are provided with the complementary ribbed 15 grooves or recesses 6 and 7, which co-operate when the sections or parts are assembled to provide the wire-ways 8, it being understood that the wires 9 are placed in these wire-ways and clamped between the 20 two parts or sections of the insulator.

As stated hereinbefore, these two parts or sections of the insulator are mounted on the securing means 5 which extends entirely therethrough, having the headed portion 10 at one end and being provided with a stop or abutment of some sort below the bottom or base section. In the disclosure made in the drawings, I show the base or bottom section provided with the socket or recess 11 and 25 the stop or abutment member in the form of a washer 12 which fits within this socket or recess 11. This washer member 12 is frictionally and tightly secured to the securing means 5 at 30 such a position as to permit the relative movement of the two sections or parts of the insulator so as to permit the movement of a wire laterally into the wire-ways and at the same time, prevent an entire separation of 35 the two sections from each other or their accidental removal from the securing means.

In order to provide means for holding the two sections or parts of the insulator in proper position relative to each other, I 40 provide in the base or bottom section 2, the socket or recess 13 having all of its walls inclining downwardly and converging toward each other, so that the socket is somewhat tapered and restricted at its lower end.

45 I also provide the top or cap section 1, with a correspondingly shaped stud or projection 14, the sides and ends of which are inclined downwardly, so that the stud or projection tapers to fit the socket or recess 13. The 50 stud or projection 14 and the recess 13 are both of general rectangular shape in cross-section, so that as long as the stud projects into the recess to any extent at all, no relative rotary movement of the parts can occur. This insures that they will always be 55 in proper alignment so that the wire-ways will always be complete. Of course it is understood that the relative position of the 60 stud or projection 14 and the socket or recess 13 may be reversed.

It is to be noted that the opening 4 through the insulator passes through the central part of the stud or projection 14 and also through the central part of the socket or recess 13.

It is also to be noted that the stud or projection 14 is of such length and the socket or recess 13 of such depth as to permit the movement of the two sections of the insulator a sufficient distance apart to permit the lateral movement of a wire into the wire-ways without withdrawing the stud or projection entirely from the socket or recess. This is prevented by the proper positioning of the stop or abutment member 12, as indicated in dotted lines in Figure 2, so that after the wire is in position and when the securing means is driven, the parts will always assume their proper position for holding and securing the wire without the necessity of further manipulation or attention by the installer.

In installing wires with insulators of this character, it is only necessary for the installer to drive the securing means into the surface over which the wiring is being installed, so as to hold the insulator in position. He then separates the two parts or sections of the insulator sufficiently to permit the application of the wire therebetween and into its proper position in the wire-ways. Then the securing means is completely driven whereby the wire is clamped firmly between the two sections of the insulator and securely held in position. The stud or projection 14 forms an insulation around the nail so as to prevent short circuit, due to the wire coming in contact therewith.

It is seen, therefore, that I have provided a simply constructed two-part insulator, in which the parts are always held in position, ready for application and on the securing means, the means being provided to prevent the separation of the sections from the securing means, but permitting their relative movement so that the wire may be applied therebetween. The stop or abutment member 12 is held in position with sufficient force to prevent accidental or unintentional separation of the sections, but should the sections become damaged, they may be withdrawn from the securing means with the use of sufficient force, so that all of the functions and advantages of the two-part or split insulator are retained.

The wire-ways extend along the long face or side of the stud or projection 14 so that they are properly placed and held in position.

What I claim is:

1. A two part insulator having complementary grooves forming wire ways when assembled, one of the parts of the said insulator being provided with an oblong recess 130

and the other part having a substantially oblong stud extending into the recess and adapted to maintain the complementary grooves in alignment and being of sufficient length to permit relative movement of the two parts to allow a wire to be introduced into and removed from the said grooves without disengaging the lug from the recess, and securing means passing through the two parts of the insulator and provided with means for preventing complete separation of the said parts but permitting sufficient relative movement of the said parts of the insulator to enable a wire to be placed in and removed from the said grooves.

2. A two part insulator having complementary grooves forming wire ways when assembled, one part of the insulator being provided with a tapering oblong recess and the other part being provided with a tapering oblong stud extending into the recess and being of sufficient length to permit relative movement of the two sections to enable a wire to be placed in and removed from the said grooves without disengaging the stud from the recess, whereby the stud is adapted to maintain the grooves in alignment when the parts of the insulator are either contiguous or separated, and securing means passing through the two parts of the insulator and provided with means for preventing complete separation of the two parts from each other and from the securing means but permitting sufficient relative movement of the two parts to place a wire in and remove the same from the said grooves.

3. A two part insulator having complementary grooves forming wire receiving ways, one of the parts being provided with an oblong recess having inclined side and end walls and the other part having a substantially oblong stud extending into the recess and provided with inclined side and end faces, said stud being of sufficient length to permit relative movement of the said parts to permit a wire to be placed in and removed from the said grooves without disengaging the stud from the recess, whereby

the stud and the recess are adapted to maintain the said grooves in alignment in either position of the said parts, and securing means passing through the two parts of the insulator and provided with means for preventing the complete separation of the said parts from each other and from the securing means but permitting sufficient movement of the two parts to place a wire in and remove the same from said grooves.

4. An insulator formed of sections having bores therethrough, fastening means loosely inserted through the bores, and retaining means carried by and frictionally engaging the fastening means and movable on the latter by engagement therewith of the surface against which the insulator is applied, the retaining means holding the sections in loose association on the fastening means and also holding all the parts of the insulator in proper relation to each other prior to the application of the insulator.

5. An insulator formed of sections, a fastening device loosely inserted through and normally holding the sections in associated relation, the fastening device having a smooth surface construction, and retention means adjustably and frictionally held on said fastening device and operating to primarily hold all the parts of the insulator intact on the fastening device prior to the application of the insulator, the retention means being shifted on the smooth surface of the fastening device by engagement thereof with the surface against which the insulator is applied.

6. An insulator formed of two sections, and a nail inserted loosely through the sections and provided with a washer frictionally engaging the same to hold all the parts of the insulator in associated relation prior to the application of the insulator, the nail being slideable through the two sections and the washer when it is applied and the washer contacting with the surface against which the insulator is applied as the nail is driven into securing position.

CHARLES W. KETTRON.
